UNITED STATES PATENT OFFICE.

WALTER V. REICHARD, OF PAOLA, KANSAS.

ROD-LINE STRETCHER AND WELL BUMPER.

Application filed October 10, 1921. Serial No. 506,702.

To all whom it may concern:

Be it known that I, WALTER V. REICHARD, a citizen of the United States, residing at Paola, in the county of Miami and State 5 of Kansas, have invented certain new and useful Improvements in Rod-Line Stretchers and Well Bumpers; and I do declare the following to be a full, clear, and exact description of the invention, such as will enable 10 others skilled in the art to which it appertains to make and use the same.

This invention relates to an improved device for use in connection with a pull-line for operating a pump of an oil well, and one 15 object of the invention is to provide a device by means of which the pull-line may be let out and thus the pump permitted to strike in the bottom of the well so that the pump may be bumped and thus a valve which has 20 hung be shaken loose and caused to operate properly. It often happens that the valve will be clogged by thick oil or by some other obstructions and in order to permit of the pump being lowered and then again very 25 easily raised to the normal position that this device was produced.

Another object of the invention is to provide a device which can be used in connection with a pull-line of an ordinary construction and may be substituted for the usual 30 link or elongated hook which connects the end of the pull-line with a ring at the end of the power line.

Another object of the invention is to provide 35 a device which will consist of a comparatively few number of parts, all of which will be simple in construction and easy to operate and properly adjust during lowering and raising of the pump in the well.

40 This invention is illustrated in the accompanying drawings, wherein:

Figure 1 is a perspective view showing the attachment in place and the pull-line in one position.

45 Figure 2 is a perspective view showing the pull line moved to another position.

Figure 3 is a perspective view showing the pull-line in still another position.

50 Figure 4 is a sectional view through one of the grapples forming a part of the attachment.

This device is for use in connection with a conventional structure of pump operating power line and pull-line. In oil wells, it is 55 customary to provide a power line 1 which is connected with a suitable source of power so

that it may be let out and then drawn in and this operation repeated. This power line has one end connected with a ring 2 with which any number of pull-lines 3 may be 60 connected. Each of the pull-lines 3 is provided at one end with a grapple 4 having at its free end a hook 5 and intermediate its length provided with a spur or hook 6. Under ordinary circumstances, the pull-line 3 65 is to be connected with the ring 2 by means of a link or bar 7 provided at its ends with hooks 8 for engaging the ring 2 and hook 5. In the present illustration, there has been shown two of the pull-lines, one of which is 70 connected with the ring 2 by means of this link 7 and the second of which is connected with the ring by means of the improved attachment to be hereinafter described. Below the pull-lines or rod lines 3, there has been 75 shown what is known as an off-hook and is in the form of an anchor rod 9 which will be suitably anchored to the ground and will have its upper free end portion provided with an eye 10.

When the well is to be bumped, the link or hook 7 is to be removed and the device which forms the subject matter of this invention substituted. This device consists of a cable or chain 11 which is provided at one end with a ring 12 for engaging the hook 5 at the free end of the grapple 4. Grapples are mounted upon this chain 11 as shown in Figs. 1, 2, 3 and 4 and each of these grapples consists of a hook 13 which is loosely 90 mounted upon a ring or hanger 14 through which passes the chain 11. This ring or hanger is provided with a handle or tongue extension 15 by means of which the hanger may be easily moved along the chain. In 95 order to permit the grapples to be releasably but securely held in place upon the chain, each hanger is provided with a slot 16 which leads from the eye 14 into the handle 15 and is of the proper width to permit a link of chain to be placed in the slot with an adjoining link engaging the face of the handle upon opposite sides of the slot and prevent the chain from moving through the guard in one direction. It will thus be 100 seen that the grapples of this chain may be secured in the desired positions when the device is in use.

When the oil pump is being operated, the pull-line 3 is connected with the ring 2 of 110 the power line 1 by means of the hook 7 and as the power line 1 is let out and drawn

in, the pump will be operated in the usual manner. When the pump becomes clogged with thick oil and it is desired to bump the well, the improved device will be brought to a point upon the field adjacent to the position of the hook 7. The rod 9 will then be swung upwardly so that when the power line is let out, the spur 6 of the grapple 4 will engage the eye 10 as shown in Fig. 1. The line 3 will thus be held by this hook or grapple 4 and the hook 7 can be easily removed. The ring 12 will be placed upon the hook 5 and the end grapple of the chain will have its hook 13 connected with the ring 2 of the power line 1. The chain will be moved into the notch of the hanger of this end grapple and upon the return movement of the power line 1, the pull-line 3 will be drawn upon and the hook 6 moved out of engagement with the eye. When the power line 1 again advances to lower the pump into the well, the power line and pull line 3 move to lower the pump in the well, and the hook of the second grapple of the chain will engage the eye 10 as shown in Fig. 3. The line 3 will be held by this hook and as the power line continues to advance, the chain may be released from the hanger of the first grapple and slipped through the eye 14 until the desired amount of chain has been let out. Upon the return stroke, this slack between the two grapples will be taken up and the hook of the second grapple will be moved out of engagement with the eye 10. When the power line is again let out, the pump should strike the bottom of the well as the power line is let out and drawn in, and the bumping of the pump in the bottom of the well will cause the valve to be severely shaken and any obstructions thus removed. Of course, if it is found that the pump does not strike properly in the bottom of the well, the hook of the second grapple can be again brought into engagement with the eye 10 and the proper adjustment made. After the bumping has been completed, the hook of the second grapple will be first brought into engagement with the eye 10 and the grapple which engages the ring 2 will then be moved along the chain and locked in engagement with the chain. The pull of the next rewind stroke will bring the hook 6 into position for engaging the eye 10 and with the line 3 held by the grapple 4, the attachment can be removed and the hook 7 replaced. It should be further noted that in case the line 3 should break, the hook 7 can be removed and the two end portions of the line brought together and spliced and the attachment then put in place so that the pump can be drawn upwardly from the well and the hook 6 engaged with the eye 10. After this hook is in engagement with the eye 10, the attachment can be removed and the hook 7 put in place. It

will thus be seen that with this device, a pump which has its valve clogged can be easily freed of the obstruction and again put in operation. It will also be seen that by means of this device, a splice can be easily made in a broken line.

I claim:

1. A device of the character described comprising a chain, an attachment element at one end of said chain, and grapples slidably mounted upon said chain and adapted to be interlocked with the chain and releasably held against movement longitudinally of the chain in one direction. 75

2. A device of the character described comprising a cable, attaching means at one end of said cable, a grapple slidably mounted upon said cable and releasably held against movement in one direction, and a second grapple slidably mounted upon the cable between said attaching means and first mentioned grapple and releasably held against movement in one direction. 80 85

3. A device of the character described comprising a chain, an attaching element at one end of said chain, and grapples carried by and adjustable longitudinally upon said chain, each of said grapples comprising a hanger slidably mounted upon said chain and adapted for interlocking engagement with the chain to releasably hold the guard housing against movement longitudinally of the chain in one direction, and article engaging means carried by the hanger below the chain. 90 95 100

4. A device of the character described comprising a chain, an attaching element at one end of said chain, and grapples carried by and adjustable longitudinally upon said chain, each of said grapples comprising a hanger slidably mounted upon said chain and having an eye receiving the chain and a handle extending from the eye and cut from the eye to provide a chain securing slot whereby the grapple may be held against movement in one direction when a portion of the chain is moved into the slot, and article engaging means carried by the eye of said hanger. 105 110

5. A device of the character described comprising a chain, an attaching element at one end of said chain, and grapples carried by and adjustable longitudinally upon said chain, each of said grapples comprising a hanger having a chain receiving eye having a slotted handle extension, and a hook loosely mounted upon said eye, the chain extending through the eye whereby the chain may be moved into the slot and hold the grapple against sliding movement upon the chain in one direction. 115 120 125

In testimony whereof I have hereunto set my hand.

WALTER V. REICHARD.
